US00D760753S

(12) **United States Design Patent**
Cheng et al.

(10) **Patent No.:** US D760,753 S
(45) **Date of Patent:** ** Jul. 5, 2016

(54) **DISPLAY SCREEN OR PORTION THEREOF
WITH GRAPHICAL USER INTERFACE**

(71) Applicant: **Huawei Device Co., Ltd.**, Shenzhen (CN)

(72) Inventors: **Liang Cheng**, Beijing (CN); **Kei Yip Dennis Poon**, Shenzhen (CN)

(73) Assignee: **Huawei Device Co., Ltd.**, Shenzhen (CN)

(**) Term: **14 Years**

(21) Appl. No.: **29/468,446**

(22) Filed: **Sep. 30, 2013**

(51) **LOC (10) Cl.** 14-04

(52) **U.S. Cl.**

USPC **D14/486**

(58) **Field of Classification Search**

USPC D14/485-495; 715/700, 703, 710, 711, 715/731, 743, 758, 780, 838, 840, 845, 846, 715/864, 759, 762, 763, 765, 770, 779, 783, 715/786, 787, 795, 810, 818, 819, 820, 835

(57) **CLAIM**

The ornamental design for a display screen or a portion thereof with a graphical user interface, as shown and described.

DESCRIPTION

The FIGURE is a front view of a display screen or portion thereof with a graphical user interface showing our new design.

The broken lines shown in the drawing represent portions of the display screen or portion thereof with graphical user interface that form no part of the claimed design.
